UNITED STATES PATENT OFFICE.

SELDEN LEWIN CLAWSON, OF SALT LAKE CITY, UTAH.

FUME-ARRESTER.

1,083,057.

Specification of Letters Patent.

Patented Dec. 30, 1913.

Application filed February 10, 1911. Serial No. 607,851.

To all whom it may concern:

Be it known that I, SELDEN I. CLAWSON, a citizen of the United States, residing at Salt Lake City, in the county of Salt Lake, State of Utah, have invented certain new and useful Improvements in Fume-Arresters, of which the following is a description, reference being had to the accompanying drawing and to the letters and figures of reference marked thereon.

My invention relates to improvements in fume arresters for metallurgical furnaces.

The object of my invention is to provide a fume arrester of this character, in which a liquid is caused to move through a restricted passage, sucking the gases or discharge of a metallurgical furnace with it, and then passing through a zigzag passage until the liquid has absorbed all of the des- sired products of the fumes.

Another object of my invention is to discharge the liquid upon flat blades, whereby it is thoroughly broken up and caused to thoroughly mix with the gases, so intimately that in the movement thereof through the zigzag passage the fumes will be absorbed by the solution.

In the accompanying drawings,—Figure 1 is a vertical sectional view of my improved fume arrester; Fig. 2 is a horizontal sectional view, taken on the line 2—2 of Fig. 1, and showing the top plate of the upper centrifugal wheel broken away; Fig. 3 is a vertical sectional view of a modified form of fume arrester, embodying the same principle; Fig. 4 is a vertical sectional view of another modified form of fume arrester, embodying the same principle as that shown in Figs. 1 and 3. Fig. 5 is a vertical sectional view of another modified form of the fume arrester.

Referring now to the drawings, 1 represents a tank which may be of any form, but preferably circular, as shown in Fig. 2 of the drawings, and in which a liquid is held. Supported by the upper edge of the tank by means of brackets 2 is an electric motor 3. Carried by the lower face of said motor are screw-threaded rods 4, upon which are screwed turn buckles 5, which are screwed upon screw-threaded rods 6, carried by the

bell 7, said bell extending within the tank adjacent the lower end. The electric motor, as shown, has its shaft 8 passing through a packed bearing 9, and said bearing extends within the bell. The lower end of the said shaft 8 within the bell has rigidly secured thereto the vertically disposed centrifugal tube 10, which extends down within the tank adjacent to the bottom thereof. The upper end of said tube has around its entire circumference radially extending passages 11, which project outwardly some distance. These passages are preferably formed by an obliquely arranged lower circular plate 12 surrounding the tube 10 and the upper horizontal disk-shaped plate 13, which closes the upper end of the tube 10 and extends out a slight distance beyond the lower obliquely arranged plate 12.

Between the upper and lower plates 13 and 12 are vertical radially arranged plates 14, which form the passages 11. The plates 14 being radially arranged, it will be seen that the passages 11 gradually increase in width outwardly.

Within the lower end of the tube 10 are blades 15, preferably of propeller form, which lift the liquid upwardly within the tube, as will be hereinafter more fully described.

The outer vertical portion of the bell 7 has its inner face of a zigzag form. Supported by the bell by means of bolts or rivets 16 is a ring-shaped member 17, which is spaced from the top of the bell 7 by the curved radially arranged blades 18. The upper face of the member 17 is convex, as indicated at 17', and as shown starts at a point below the passages 11. The outer edge of said member 17 is provided with a downwardly extending flange 19, which extends some distance below the lower end of the bell 7. The outer face of said flange is zigzagged to correspond with the zigzagged inner face of the bell, and forms the zigzagged passage 20 between the same. The turn buckles 5 allow for the vertical adjustment of the bell, and thereby the passage 21 between the convex face 17' of the ring 17 and the radially arranged passages 11 may be increased or decreased as desired, whereby the amount of

2
fumes to be mixed with the liquid may be readily regulated.

Extending through the bell 7 above the plate 17 is a pipe 22, which conveys the fumes from the furnace. A second pipe 23 extends through the bottom of the tank 1, and conveys the fumes from the furnace to the space 24 below the bell. The tank is partially filled with a liquid and the level 10 of the same is above the lower end of the flange 19, but below the lower end of the bell 7. The fumes from the metallurgical furnace pass within the bell through the pipes 22 and 23, and fill the space 24 within 15 in the bell, the liquid serving as a seal to prevent the escape thereof around the lower edge of the flange 19.

When the motor is started, it will be seen that the tube 10 is rapidly rotated and the 20 blades 15 lift the liquid by centrifugal force upwardly, and discharge it from the tube through the radial passages 11. As it passes therefrom it enters the contracted passage between the bell 7 and convex face 17'. This 25 causes a suction of the gases or fumes within the space 24 through the passage 21, and also through a passage above the plate 13. The liquid striking against the curved blades 18 is broken up, and thoroughly 30 mixes with the fumes. The zigzagged passage 20 also causes a more thorough mixing of the fumes and liquid, and by the time the lower end of the passage is reached the liquid has absorbed all of the desired products 35 in the fumes. The liquid passes back into the tank, while the worthless fumes pass around the lower end of the bell and out of the tank, as indicated by the arrows in Fig. 1.

40 In the modification shown in Fig. 3, the tank 1 is provided at the center with an opening 25, having an upwardly extending sleeve 26, surrounding the same. The motor or pulley shaft 27 extends through the 45 sleeve, and is supported from below the tank. The centrifugal tube 28 has a central passage 29 therethrough, into which extends the sleeve 26. The space 30 surrounding the passage 29 is provided with blades 31, which, 50 like the blades 15 in Fig. 1, are of propeller form. The space 30 at its upper end is provided with radially arranged passages 32, formed exactly alike, and acting in the same manner as the passages 11 in the preferred 55 form of my invention. The bell 33 has a zigzag or irregular upper face 34, and its semi-circular inwardly extending lower end 35 is within the tank. The circular plate 36 has an irregular form, to correspond with the face 34 of the bell, and forms the zigzag horizontal passage 37 opposite to the passages 32, carried by the centrifugal tube 28. The plate 36 about midway its inner and outer edges is provided with a

downwardly extending flange 38, which extends a considerable distance below the lower end of the bell and below the level of the liquid within the tank 1. The plate 36 on the inside of the flange 38 is provided with a series of openings 39, which allow the liquid which has not become thoroughly broken up and mixed with the fumes, to pass back into the tank through the space within the bell filled with fumes, and thus absorb a certain amount of fumes. Extending 75 through the side of the tank is a pipe 40, which also passes through the flange 38 and conveys the fumes from the furnace to the space at the center of the bell.

In the modification shown in Fig. 4, the 80 tube 41 and the passages 42 are arranged the same as the tube 10 and passage 11 in Fig. 1. The shaft 43 extends to the bottom of the tube and carries the propeller blades 44, which are the same as those shown in the 85 other two forms. The bell 45 has the zigzag walls 46, which extend a slight distance within the tank. The cylindrical member 47 has the zigzag wall 48 corresponding with that of the bell and forming the passage 49. The cylindrical member 47, as shown, has its upper end considerably below the passages 42, and is also at a different angle from the bell, to form an enlarged 90 exit to the zigzag passage 49. The lower 95 end of the zigzag portion of the member 47, in alignment with the lower end of the bell, is provided with an inwardly extending horizontally arranged portion 50, terminating in the downwardly extending vertical 100 flange 51, which extends into the liquid within the tank and forms the seal. The bell 45 adjacent the passages 42, is provided with the blades 52, similar to the blades 18, Fig. 2, against which the liquid is thrown 105 by centrifugal force and broken up. The liquid then passes downwardly through the fumes in the space in the bell, and enters the zigzag passage 49. From this passage it passes to the tank, carrying with it the 110 fumes and absorbing the desired products. As will be seen some of the liquid will not enter the passage 49, but will pass downward directly through the fumes in the bell, and thus absorb the products. The bell is 115 supplied with fumes by the pipe 53, the same as in the other forms. The shaft 43 is provided with a drive pulley 43' by means of which the shaft is rotated.

In the modification shown in Fig. 5, the 120 central shaft 54 is mounted in suitable bearings 64 in a supporting frame 65, and said shaft is hollow and closed at its lower end by the plug 71. At the upper end the shaft is connected to a box 55 by a gas-tight joint. 125 Said box is connected by a pipe 66 with the furnace so that the fumes will pass into the box and down through the hollow shaft.

Extending rearwardly from the hollow shaft are a plurality of suction pipes 56. A wheel 57 is carried by the hollow shaft 54 and rotates therewith. Said wheel is formed with spaced members 58 and 59, which are shaped so as to form a zigzag passage 60 between the same. The pipes 56 each are connected to the pipe 54, and fumes are therefore led through the sections of the wheel. 10 Radial partitions 62 are placed in the bottom of the tank underneath the wheel 59, to prevent the liquid from whirling around with the wheel. The liquid is lifted by a propeller 63 within a cylindrical member 67 carried by the lower member 59 and forced outward between the sections of the wheel, where it comes into contact with the fumes. The lower end of the tube 54 has secured thereto a member 68 having a hub 69 screwed thereon, and to which is secured the member 58. The said hub is connected to the cylindrical member 67 by means of the web 70.

Having thus described my invention, what I claim as new and desire to secure by Letters Patent, is:

1. A fume arrester comprising a tank adapted to hold a liquid, a bell supported within the tank and sealed by the liquid therein, means for supplying the fumes to the bell above the liquid, a rotatable tube within the bell, blades within the lower end of the tube, the upper end of the tube having radially extending discharge passages in communication with the tube, and the bell having a circumferential passage adjacent the ends of the discharge passage, carried by the tube, whereby the liquid is discharged from the tube by centrifugal force to the circumferential passage and draws with it fumes from the bell.

2. A fume arrester comprising a tank adapted to hold a liquid, a bell supported within the tank and sealed by the liquid therein, means for supplying the fumes to the bell above the liquid, a rotatable tube within the bell, blades within the lower end of the tube, the upper end of said tube having outwardly extending radially arranged discharge passages, the bell having a circumferential zigzag passage adjacent the ends of the passage carried by the tube, baffle plates within said circumferential passage, and means for rotating said tubes, whereby the liquid is discharged from the tube by centrifugal force into the circumferential passage, and draws with it fumes from the bell and causes a thorough mixing of the liquid and fumes, whereby the liquid absorbs the desired fumes.

3. A fume arrester comprising a tank adapted to hold a liquid, a bell supported within the tank and sealed by the liquid therein, means for supplying the fumes to

the bell above the liquid, a rotatable tube 65 within the bell, blades within the lower end of the tube, the upper end of the tube having outwardly extending radially arranged discharge passages, the bell having a passage adjacent the ends of the passages carried by the tube, baffle plates within said circumferential passage, means for raising and lowering the bell to vary the fume passage between the circumferential passage and the radial passages, and means for rotating the tube, whereby the liquid by centrifugal force is thrown from the tube into the centrifugal passage.

4. A fume arrester comprising a tank holding a liquid, a bell supported in the tank and sealed by the liquid, means for discharging fumes within the bell above the liquid, a centrifugal tube within the bell and having radial discharge passages at its upper end, the bell having a circumferential passage surrounding the radial passages carried by the tube, and of a greater width than the tube passages, and means for raising the bell, whereby the passage for the fumes is varied.

5. A fume arrester comprising a tank holding a liquid, a bell supported in the tank and sealed by the liquid, means for discharging fumes in the bell above the liquid, the bell having a circumferential passage at its upper end, and centrifugal means within the bell and extending within the circumferential passage carried by the bell for lifting the liquid and discharging it into the circumferential passage, and means for raising the bell, whereby the fume passage entering the circumferential passage is decreased.

6. A fume arrester comprising a tank holding a liquid, a bell supported within the tank and sealed by the liquid, said bell having an outlet for the fumes, a centrifugal means for lifting the liquid from the lower end of the tank and mixing it with the fumes, and an inlet for the fumes in the bell above the discharge of the centrifugal means.

7. A fume arrester comprising a tank holding a liquid, a motor case supported by the tank, a bell within the tank and sealed by the liquid, turn buckle connections between the bell and the motor case, means for discharging the fumes to the bell, a shaft extending through the bell, a centrifugal means for lifting the liquid and mixing it with the fumes, whereby the vertical movement of the bell by the turn buckles varies the amount of fumes mingled with the liquid.

8. A fume arrester comprising a tank adapted to hold a liquid, a bell supported within the tank and sealed by the liquid therein, a rotatable tube within the bell, means for supplying fumes to the bell above the liquid, blades within the lower end of the

tube, the upper end of the tube having outwardly extending radially arranged discharge passages, the bell having a passage adjacent passages carried by the tube, 5 curved baffle plates within said passage, said passage terminating in a zigzag passage, means for raising and lowering the bell to vary the fume passage and the radial passages, and means for rotating the liquid by

centrifugal force thrown from the tube into 10 the passage.

In testimony whereof I affix my signature, in presence of two witnesses.

SELDEN IRWIN CLAWSON.
